UNITED STATES PATENT OFFICE.

WALTER V. TURNER, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

SANDING DEVICE.

1,126,918.

Specification of Letters Patent.

Patented Feb. 2, 1915.

Application filed October 9, 1912. Serial No. 724,724.

To all whom it may concern:

Be it known that I, WALTER V. TURNER, a citizen of the United States, residing at Edgewood, in the county of Allegheny and State of Pennsylvania, have invented new and useful Improvements in Sanding Devices, of which the following is a specification.

This invention relates to sanding devices, and more particularly to a valve mechanism for controlling the supply of sand to railway rails to assist in stopping and starting trains.

The principal object of my invention is to provide an improved sand valve mechanism in connection with a brake valve device which is adapted to be operated at will in any position of the brake valve handle.

In the accompanying drawing; Figure 1 is a sectional view of an engineer's brake valve, showing the improved sand valve mechanism applied thereto and Fig. 2 a plan view thereof.

The brake valve may be of the usual construction comprising a casing 1 having a valve chamber 2 containing a rotary valve 3 adapted to be operated by brake valve handle 4, the valve chamber 2 containing fluid at main reservoir pressure.

According to my improvement, a sand valve casing 5 is screwed into a threaded aperture formed in the cylindrical side wall of the brake valve casing 1, so that an opening 6 from valve chamber 7 of the sand

valve casing 5 communicates with the brake valve chamber 2. Within the valve chamber 7 is mounted a valve 8 subject to the pressure of a spring 9 tending to maintain the valve 8 on its seat and said valve is adapted when opened to supply fluid from the brake valve chamber 2 to a pipe 10, the admission of fluid to which is adapted to effect the discharge of sand on the rails.

The sand valve 8 is provided with a stem 11 which projects out radially through an aperture in the casing 5, so that by pressing the stem inwardly, the valve 8 may be lifted from its seat.

Pivots mounted on a lug 12 carried by a brake valve casing 1 is a curved segment bar 13, so located that when the bar is pressed inwardly, the same will engage and force inwardly the valve stem 11. The end of the bar 13 opposite to the pivotal end is preferably supported on a lug 14 and

said bar is of sufficient length to cover all operating positions of the brake valve handle from release position to emergency position. The brake valve handle 4 is pivoted to the stem 15 of the rotary valve 3 and is provided with a downwardly projecting arm 16 adapted, upon vertical movement of the brake valve handle 4 on its pivotal support, to engage with the bar 13 and press the same inwardly. 65

It will now be evident that in operation, the engineer can manipulate the brake valve handle in the usual manner to control the brakes and when it is desired to sand the rails, the engineer may, by pressing down 70 on the brake valve handle in any position in which the handle may be, cause the valve stem 11 to be forced inwardly by the inward movement of the bar 13, so that the sand valve 8 is lifted from its seat to admit 75 fluid under pressure to the sand pipe 10.

In addition to the usual operation of the sand valve by pressing down on the brake valve handle, the sand valve is adapted to be automatically operated upon movement 80 to emergency application position, and for this purpose, the bar 13 is provided with a thickened end portion 17 adjacent to the emergency position, so that the movement of the brake valve handle 4 to emergency 85 position causes the arm 16 to engage said thickened portion and thereby force the bar 13 inwardly without depressing the brake valve handle.

Having now described my invention, what 90 I claim as new and desire to secure by Letters Patent, is:—

1. The combination with a brake valve device provided with an operating handle, of a sanding mechanism and means adapted 95 to be operated by said handle in any position of the handle for effecting the operation of said sanding mechanism.

2. The combination with a brake valve device provided with a handle for operating 100 the brake valve upon movement in one plane, of a sanding mechanism and means adapted to be operated upon movement of the handle in another plane for effecting the operation of said sanding mechanism. 105

3. The combination with a brake valve device provided with a handle for operating the brake valve upon movement in a horizontal plane, of a sanding mechanism and means adapted to be operated by movement 110

of the handle in a vertical plane for effecting the operation of said sanding mechanism.

4. The combination with a brake valve device provided with an operating handle pivoted for vertical movement, of a sand valve and means operated by the vertical movement of said handle for actuating said sand valve.

10 5. The combination with a brake valve device comprising a rotary valve, a stem for said valve, and an operating handle pivoted to said stem, of a sand valve and a movable bar adapted to be actuated upon movement of the handle on its pivot for operating said valve.

6. The combination with a brake valve device comprising a rotary valve, a stem for said valve, and an operating handle pivoted to said stem, of a sand valve, a pivotally mounted bar adapted to engage said valve, and a lug on said handle for engaging the bar to actuate the same and thereby said valve upon movement of the handle on its pivot.

20 7. The combination with a brake valve device comprising a horizontally movable

rotary valve, a stem for said valve, and an operating handle pivoted to said stem for vertical movement, of a sand valve, a horizontally movable bar for actuating said valve upon vertical movement of the handle, and means on said bar adapted to be engaged by the handle upon horizontal movement to one position for also actuating said sand valve.

30 8. The combination with a brake valve device comprising a horizontally movable rotary valve, a stem for said valve, and an operating handle pivoted to said stem for vertical movement, of a sand valve, a horizontally movable bar for actuating said valve upon vertical movement of the handle, and a thickened portion on said bar adapted to be engaged by said handle upon movement to emergency application position for also actuating said sand valve.

40 In testimony whereof I have hereunto set my hand.

WALTER V. TURNER.
